UNITED STATES PATENT OFFICE.

ARTEMAS L. DAWSON, OF ELK POINT, DAKOTA TERRITORY, ASSIGNOR OF
TWO-THIRDS TO CHARLES H. FREEMAN, OF SAME PLACE, AND GEORGE
BOHNER, OF CHICAGO, ILLINOIS.

MACHINE FOR ATTACHING METAL COLLARS TO LAMPS.

SPECIFICATION forming part of Letters Patent No. 315,745, dated April 14, 1885.

Application filed May 14, 1884. (No model.)

To all whom it may concern:

Be it known that I, ARTEMAS L. DAWSON, of Elk Point, in the county of Union and Territory of Dakota, have invented certain new and useful Improvements in a Machine for Attaching Collars to Lamps; and I hereby declare the following to be a full, clear, and exact description of the same.

My present invention is an improvement upon the device for which Letters Patent of the United States No. 289,509 were granted to me December 4, 1883. The purpose of my improved machine is identical with that described in my aforesaid patent; but the mechanism by which the operative parts are actuated differs in part very materially in the two devices. Among other things, it was thought at the time of making the application upon which my aforesaid patent was granted, and until recently, that the operation of the machine necessitated the employment of at least two burnishers, whereas it now appears that for certain purposes with my present device but one burnisher is required.

Referring to the drawings, Figure 1 is a front elevation of my improved machine, having a part of a detail broken away to show its construction; Fig. 2, a vertical section of the device shown in Fig. 1, taken on the line 2 2 of the same and viewed in the direction of the arrow-heads; Fig. 3, a transverse vertical section showing the construction of the burnisher mechanism and parts operating the same; Fig. 4, a broken portion of a detail showing the manner of its operation; Fig. 5, a detail view showing the manner of linking the burnishers together, whereby their oscillatory motion with respect to each other is effected and limited; Fig. 6, a plan view of a detail; Fig. 7, a vertical section taken on the line 7 7 of Fig. 6, viewed in the direction of the arrow-heads; Fig. 8, a sectional view of a detail; Fig. 9, a perspective view of a broken portion of a detail showing the preferred manner of its construction; Fig. 10, a sectional view of a modification, and Fig. 11 a vertical central section of the machine.

The position contemplated for my former

machine is horizontal, whereas that of my present machine is intended, as represented in the accompanying drawings, to be vertical.

The principal improvement in the present over my former device is due to the manner of operating the part of the latter shown and described as the "lever M," and which served therein, as it does now, (though without in its improved form moving the shaft hereinafter described,) the purpose of advancing and retracting the burnishing mechanism; but in my said former device the proper control of its operation demanded on the part of the operator a greater delicacy of muscular sense than should be depended upon always to exist for the purpose of producing results of invariable perfection. In the machine as at present constructed, and as will be seen in the following description, manipulation of a lever, K, (corresponding with the lever K in my patent referred to,) by means of which the burnisher-tips are caused to cross each other or are expanded, operates the said lever M to advance the burnisher-tips at the proper time.

A, Figs. 2 and 11, is a hollow rotary shaft supported within bearings *v u*, secured upon or cast with a cylinder, A', made hollow for the sake of lightness, and forming the bed of the machine. A casting, *w*, is adjustably secured upon the part A', and is provided with bolt-holes in its outer end to receive screw-bolts *w'*, by means of which casting the machine may be supported in a vertical position against a post, table, or the like. Rods *t* and *t'* extend from the bearings *u* to a plate, L, hereinafter described, and rods *t* and *t'* extend from the bearings *v* to a cross-piece, *s*, the rods and cross-piece affording a light but substantial frame for the support of various of the operative parts of the machine. The shaft A carries a pulley, B, and is rotated by connecting the latter with suitable driving-power by means of a belt or by other appropriate gearing.

Burnishers, comprising each a blade, C, having one extremity formed into a finger bent to a right angle, or nearly so, to provide a burnisher-tip, *r*, are inserted into the shaft A

from its lower end in a manner to permit the parts r to project beyond the end of the shaft. The shape of the blades C is somewhat tapering toward their upper extremities to permit 5 their outer edges to lie parallel with the inside of the shaft A , as shown in Fig. 3 of the drawings, and to cause the normal positions of the burnisher-tips, when adjusted in the manner hereinafter described, to be one upon 10 the other, projecting in opposite directions, and coincident with each other. The blades C are connected toward their upper extremities between transverse parallel plates, s , by means of screws, s' , passing through holes 15 provided in the blades and through coincident holes in the ends of each transverse plate s , the end of each blade being suitably packed against the inner surface of a plate, s , to permit the burnisher-tips r to overlap each other 20 in the manner hereinbefore described. This arrangement permits a vertical oscillatory movement of the burnishers in opposite directions with respect to each other.

When two blades C are employed, (the modified construction necessary to permit the use 25 of a single blade being hereinafter described,) the end of one of the blades is provided with a notched lateral projection, as shown by dotted lines at x , Fig. 5, which embraces a 30 pin, s^3 , passed through a longitudinal slot, s^4 , provided in one side of the shaft A and through a sleeve, F , surrounding the shaft, as will hereinafter be particularly described in another 35 connection, and also through the center of each plate s . The oscillation of the burnishers is thus limited by the obstruction afforded by the pin s^3 against the edges of the notch formed in the blade.

Each blade C is provided toward one end, 40 above the burnisher-tip r , with a lateral inward-projecting lip, to which one end of a link, q , is pivoted, the links q projecting laterally through recesses formed opposite each other in the end of the hollow shaft A , as 45 clearly shown in Fig. 11 of the drawings.

E are upward-projecting diverging arms, pivoted each toward one extremity to the projecting end of a link, q , and fulcrumed within slots, a' , formed within lateral projections extending from a collar, W , secured upon the shaft A , toward its lower extremity, to revolve with it.

G is a chain secured at each extremity to one of the arms E , toward its upper end, and 55 passing through slots formed in the shaft into the latter, as shown in Fig. 10, and over pulleys c , placed within the shaft A flatwise side by side, and having a common shaft comprising a pin, o' , passing through their center and 60 through the shaft, as shown in Fig. 3 of the drawings. The chain G extends upward within the shaft to a rod, I , contained therein, to the lower extremity of which rod the chain is secured at its center. The rod I projects beyond the upper end of the shaft A , 65 and is connected with a lever, K , hereinafter

particularly described, in a manner to permit it to rotate with the shaft, by securing a pin, l , to the end of the rod and passing it through a slot properly located in the lever K , from which slot in the lever withdrawal of the pin is prevented by passing it through a ring, k^2 , formed at a central point between the extremities of a pin, k' , which passes transversely through the lever and the slot formed therein, and providing the pin l with a head, h , all as clearly shown in Fig. 8 of the drawings. A pin, l' , passing transversely through the shaft A and through a longitudinal slot, l^2 , formed in the pin l , limits the vertical play of the 80 rod I .

D is a helical spring encircling the shaft A between the extremities of the arms E , and is confined between the sliding sleeve F and the nut H , which latter serves to adjust the 85 tension of the spring D by being screwed forward and backward upon the threaded portion y of the shaft A . The sleeve F , represented as having a portion of its body cut out for the attainment of lightness in the part, 90 and to economize metal, is caused to revolve with the shaft A by means of the pin s^3 , which passes through it and through the longitudinal slot s^4 in the shaft, which the sleeve partly covers, and whereby the latter shall have a 95 limited longitudinal reciprocal movement when operated in the manner hereinafter described.

M is a lever formed of two parallel strips, h and h' , (see Figs. 2 and 11,) which lie transversely to the shaft A , on opposite sides of the same, and are bolted together, as shown at z and z' . A pin, h^3 , passes transversely through both strips and abuts against a block, h^3 , rigidly secured upon the rod t , whereby 100 the fulcrum of the lever is formed. Toward its center the lever M is pivoted to a sleeve, F' , abutting against the sleeve F , and which, like the latter, encircles the shaft A , which 105 revolves within it, differing in this last respect from the sleeve F , which revolves with the shaft.

A link, N , is pivotally secured toward one end of the lever K , near the upper end of the machine, and is provided toward its opposite end with a longitudinal slot, g , through which a pin, g' , passes, as also transversely through both strips h and h' forming the lever M .

The construction of the plate L , hereinbefore referred to, is clearly shown in Figs. 6 and 7 of the drawings. It is supported by the rods t and t' at the lower extremity of the shaft A , and is provided with a central opening coincident with that of the hollow shaft A , to admit through it the ends of the burnishers. The lower surface of the plate is recessed around the opening to form a seat for annular plates Z , having openings of varying sizes for collars of different sizes to be adjusted, the opening for those of the largest size being 120 equal to the orifice in the plate L , while plates having smaller openings are provided for 125 130

collars of smaller size. A projection or annular flange, c^2 , is formed around the orifice of each plate Z, which is secured in position on the plate L by means of screws.

5 Although the present device is designed to serve the purpose of adjusting metal collars upon lamps, the following explanation of the operation of the parts thus far described, independent of their purpose in connection with 10 the follower mechanism hereinafter described, will, it is thought, assist in affording a ready comprehension of the operation of all the parts of the machine in performing its work as hereinafter described.

15 When the shaft A is rotated, the centrifugal force thereby generated will cause the arms E to diverge, drawing down the rod I until obstructed by the pin l' in the slot l^2 in the pin l . The limit of expansion of the arms E is 20 controlled by the length of the chain G, which is such that when the rod I is drawn down within the shaft A until obstructed, as above stated, the lower ends of the arms E, by their connection through the links q with the burnishers, will turn the extremities of the latter 25 outward and cause the burnisher-tips r to coincide with each other. The normal position of the burnisher-tips is that shown in Fig. 1, where they coincide with each other; and this 30 position is produced by the action of the centrifugal force generated by the rotation of the shaft A upon the arms E, causing the upper extremities of the latter to diverge, and hence their lower extremities to approach each other.

35 The lever K, with which the rod I is connected by means of the headed pin l rotating within a ring, k^2 , provided centrally in the pin k , which passes transversely through the lever K in a manner to cause the ring portion 40 referred to as hereinbefore described, and clearly shown in Fig. 8 of the drawings, to avoid obstruction to its revolving with the rotary shaft A, serves to draw out the rod I through the medium of a convenient mechanism 45 comprising the rope c^2 , connected to the free end of the lever K and passing over the pulley c' , supported in the cross-piece s^2 , and by drawing out the rod I, and with it the chain G attached to it, the upper extremities of the arms E will be made to approach each other, thereby spreading apart their lower extremities, and through the blocks q pulling the 50 burnisher-tips r across each other in an outward direction, and thus spreading them.

55 When the rope c^2 is released by the operator, centrifugal force will again tend to spread the arms E, thereby causing the burnisher-tips again to assume their normal position, which 60 tendency is increased by a weight, e, attached to the free end of the lever K.

If the burnisher-tips r, while the shaft A is rapidly revolving, are spread apart against the centrifugal force, which tends to maintain 65 them together, by pulling downward upon the rope c^2 to raise the free end of the lever

K, and thereby pull out the rod I and bring the upper extremities of the arms E toward each other in the manner just described, without performing any work, or, in other words, 70 without meeting with any resistance—that is to say, if no lamp and metallic collar within the same be interposed between the follower hereinafter described and plate L to receive the burnisher-tips, and by their abutment 75 against opposite sides of the inner wall of the lamp-collar limit their spreading capacity, which is otherwise controlled by the length of the chain G and the proper relative proportions of other operative features, which condition is illustrated to enable the operation of the device to be more readily understood—they 80 may first be spread apart to their full limit, since the lever K will not afford a fulcrum at its central pivotal point until the resistance 85 against the further pulling out of the rod I shall be greater than the resistance of the spring D against a forward movement of the lever M, when the obstruction afforded to further pulling out of the rod I by the abutment 90 of the lower extremity of the slot l^2 in the pin l against the pin l' will provide a fulcrum for the lever K toward its center, thereby changing it from a lever of the second class to one of the first class. Further pulling upon the rope c^2 95 will cause the link N by the abutment of the end of the slot g therein against the pin g' in the lever M to advance the latter, and with it the collars F' and F, in a downward direction, whereby, owing to the slot s^2 in the shaft, the 100 pin s^2 may also be advanced, causing the burnishers, which are pivotally connected with the links q, to project farther than normally beyond the end of the shaft A, all against the resistance of the spring D, for the reason that 105 less force is required to be exerted to overcome the centrifugal force which keeps the upper extremities of the arms E spread apart and the burnisher-tips r together during the revolution of the shaft than is required to 110 overcome the resistance of the spring D.

The mechanism by means of which a lamp-body in attaching thereto a metal collar is adjusted to the plate L consists of a follower, O, comprising a plate, preferably of circular form, 115 as shown, which is supported upon the bed A' of the machine by a rod, f, secured at one end to the center of the disk O, and passing thence through the annular head u^2 of the adjustable bearing u' , in which it has a reciprocal sliding 120 movement.

P is a lever of the second class supported by the rod f, which passes through a slot formed through its side, and which rod has a longitudinal slot, f^2 , formed through it, into which 125 a pin, f^2 , is inserted, passing also through the lever P.

A link, Q, is pivoted at one end to the bearing, as shown at x^2 , and the end of the lever P is fulcrumed to the link Q, as shown at x^3 . 130 A second lever, P', is pivoted toward its center to the end of the rod f. The pivotal move-

ment of the link Q and pivotal connection of the lever P with the same permits ready vertical movement of the straight rod f, since thereby there is no tendency to lateral strain 5 upon the latter. The lever P' is secured toward one end to the lever P by means of a bolt, i, screw-threaded toward both ends, which bolt passes through both levers and is screwed into the last-named lever, but upon 10 which bolt the lever P', owing to the size of the opening to receive the bolt, may move both vertically and laterally. A helical spring, i', encircles the bolt i, and is confined between the nut i², by means of which the tension of 15 the spring i' may be regulated at the end of the bolt and the side of the lever P'.

R is a rack, firmly secured at one end to the bearing u', as shown, upon which rests the end 20 of lever P toward the handle. A dog mechanism comprising the thumb-detent i³, which is pivoted, as shown, to the lever P, is given a tendency to engage with the rack R by the 25 resistance of the spiral spring e, which is fastened at one end to the lever P and at its opposite end to the detent, but is prevented from such engagement by the end of the angular arm S, which is pivoted near its center to the lever P in the manner shown, and which projects at one end beyond the lip of the detent 30 when the latter engages with the rack, and abuts against the lip of the detent when the latter is disengaged from the rack, in which latter position it is held by the spiral spring e', having one end secured to the arm S, to- 35 ward the opposite end of the same, the opposite end of the spring being secured to the lever P. When no resistance is encountered by the follower O, both levers P and P' act as one, and may readily be moved back and forth (or, 40 as the machine stands vertical, up and down) by means of the handle of the lever P.

The purpose of the follower mechanism, which, as hereinbefore stated, is adjustable upon the bed A' of the machine by means of 45 the bearing u', is firmly to press the lamp while the collar is being attached between the follower O and the plate L, in order that the metal collar shall be firmly held against the lamp-body while it is being attached, and that 50 the latter shall not be caused to revolve by the friction of the burnisher-tips. To effect this tight grip upon the lamp-body, the follower, after first being adjusted on the part A', to admit readily the size of lamp to be operated upon, and after the lamp-body has been placed in 55 position, is pressed against the bottom of the lamp body by pulling upon the handle of the lever P, the effect of which operation upon the parts just described is to separate the lever P 60 from the lever P', which is prevented from following the movement of its companion, owing to the pivotal attachment forming its fulcrum at the end of the rod f, and owing to the link d comprising a transverse strip secured to the lever P by a pin passing through a hole in the lever and to the lever P', also by a pin which

fits into a notch formed in its side directly opposite the hole in the lever P, each pin projecting through to the opposite side of the lever through which it passes, and being held together on the forward side of a strip like that described as on the rear side of the levers. Several notches in the lever P' opposite to 70 holes in rectilinear relation to each other in the lever P are shown, to permit adjustment 75 of the levers.

When the handle of the lever P is pulled against the resistance of the lamp-body, the link d toward the end opposite the handle of the lever pulls the corresponding end of the lever P', and causes the latter to turn on its fulcrum at the end of the rod f, and move its opposite end in the contrary direction against the resistance of the spring i' on the bolt i. A dog, d', is rigidly secured upon the side of the 85 lever P', which, when the latter is forced against the resistance of the spring f' in the manner hereinbefore described, will act upon the bent end d' of the angular arm S to turn it upon its pivot in opposition to the spiral spring e', and disengage its opposite end from contact with the lip of the detent i³, which is then forced between the teeth of the rack by the action of the spiral spring e, and the lamp-body is thus automatically held firmly between the follower O and plate L.

When a neckless lamp-body is adjusted in position, and the tubular portion of a metallic collar inserted into its orifice to be operated upon by the burnisher-tips r to spread the 100 inner edge of the tubular portion around the inner edge of the orifice, all as indicated by dotted lines in Fig. 1 of the drawings, the burnisher-tips, which project in their normal position far enough beyond the face of the 105 plate L to enter the metallic collar below its internally-screw-threaded portion in order not to injure the screw-threads, cannot, by 110 operating the lever K against the centrifugal force, be spread farther apart than the diameter of the orifice of the lamp-body with the intervening tubular portion of the collar will permit, owing to the impingement against the latter of the burnisher-tips, and when their spreading limit shall thus have been reached, the 115 resistance of the glass surrounding the collar upon the points of the burnisher-tips being greater than that to be overcome in the spring D, the particular function of which will hereinafter be explained, by continuing to pull 120 upon the lever K the burnisher-tips r will be advanced into the lamp body, spreading the edge of the collar by the pressure exerted upon them through the medium of the slot g in the link N abutting against the pin g' in the 125 lever M, which causes the sleeve F' and the sleeve F, with which the blades C of the burnishers are connected, to advance. When sufficiently far advanced into the lamp-body to have cleared the work which will have been 130 performed, the burnisher-tips are retained in such position by means of an angular pawl or

catch, *b*, pivoted, as shown, upon a rod, *T*, (another function of which will hereinafter be described,) which is riveted, as shown at *x*⁴, to the lever *M*, and advances with the latter 5 to cause the pawl or catch *b* to engage with a stop, *b'*, provided in a block, *U*, which projects laterally from the frame-rod *t'*. As soon as the lever *K* is released centrifugal force will operate in the manner hereinbefore de- 10 scribed to bring the burnisher-tips *r* together, and the weight *c* will assist in lowering the handle of the lever *K*, which, when it shall have reached its lowest point, will have produced contact of the projecting pin *b*², inserted 15 into the link *N* near its lower end, with the tail of the pawl *b*, the other end of which is retained in its engagement with the pin *b'* in the block *U* by the action of the spring *b*³, (see Fig. 4,) and will thereby have released 20 the spring *D*. With the release of the spring *D* the closed burnishers will be withdrawn from the interior of the lamp-body, but to prevent too sudden and forcible expansion of the spring, whereby injury might be done to the 25 glass lamp-body, an air-cushion is provided, which consists of the hollow cylinder *V*, closed at one end, and supported on the frame of the device, and a piston-head, *a*, upon the rod *T*.

If no spring *D* were provided, the centrifugal force generated by the rotary shaft *A* would not operate satisfactorily, even with the assistance of the weight *c*, if at all, to bring the burnisher-tips together and withdraw them from the lamp-body against the resistance of the air-cushion. Its function, therefore, is to effect by the recoil such withdrawal, and, with the assistance of the air-cushion, to do so gradually for the purpose above stated.

Mechanism is provided to permit the blades 40 *C* at their fulcrums to be contracted, and thereby avoid too great strain of the extremities of the burnisher-tips while being actuated upon the inner side of the collar and upon the lamp-body, if the burnisher-tips shall encounter 45 a sudden unevenness in the part of the lamp upon which they are operating. When this occurrence takes place, without the mechanism presently to be described, the effect would be to tend suddenly to contract the 50 burnisher-tips *r* to permit them to coincide with the decreased diameter of the orifice against the upward pressure of the end of the lever *K*, which, if great, would not permit such sudden contraction, and injury to the collar or lamp-body, or both, might be the consequence. To avoid this, each projection from the collar *W* is provided with a longitudinal slot, *a'*, and within each recess formed in a projection is a stem, *X*, slotted longitudinally, as 55 clearly shown in Figs. 3 and 10, to form a recess to receive a blade, *C*, edgewise, and is provided with an opening coincident with the hole formed in the blade *C* to receive the pivot *a'*, which also passes through the slots *a'* in 60 the projections. A helical spring, *Y*, encircles each stem *X*, and is confined between the

end of each projection and a nut, *a'*, by which the tension of the spring may be regulated.

If the burnisher-tips in advancing into the collar and lamp-body encounter a sudden unevenness, the mechanism just described will permit them to contract without exerting any material effect upon the chain or rod *I* or lever *K* by pulling the arms *E* together at their fulcrums.

The oscillatory movements of the burnishers afforded by the manner of their communication within the hollow shaft of course enable the burnisher-tips to adjust themselves to unevennesses which may occur in the under 80 side of the top of the lamp-body surrounding the orifice in the same.

The modification represented in Fig. 9 of the drawings shows the preferred way of forming the burnishers, whereby the blades *C* 85 thereof and burnisher-tips *r* are in separate pieces joined together by screws. This construction permits ready adjustment of new burnisher-tips when the old shall have become too much worn for use without necessitating 90 the removal of the blades, thereby rendering it possible to avoid a somewhat difficult operation.

If it is desired to use but one burnisher instead of two, which will be the case where 95 collars are to be attached to very small toy lamps, for which the burnishers could not be made sufficiently small to permit the use of two without weakening them too much to render them operative, or where collars are to be 100 attached to the fillers of lamps a single burnisher may be used and inserted for the purpose in the manner clearly shown in Fig. 10 of the drawings, which represents the burnisher pivoted within the shaft by means of 105 the pin *s*³, passing through the end of the blade *C*. When but one burnisher is employed, the transverse plates *s* may be omitted. For very large lamps three burnishers could be used to advantage.

It is quite obvious that the operative parts contained within the hollow shaft *A* could be arranged outside of a solid shaft, and such construction, though inconvenient and more costly than that hereinbefore described, is 115 intended to be included in my invention.

What I claim, and desire to secure by Letters Patent, is—

1. In a machine for attaching collars to lamp-bodies, the combination of the following 120 elements, viz: a frame for supporting the operating mechanism, and a rotary shaft carrying upon one extremity a longitudinally-reciprocating and laterally-oscillating pivoted burnisher adapted to pass through the collar to 125 be attached and spread the tubular portion of the collar against the inner surface of the lamp-body, as set forth.

2. In a machine for attaching collars to lamp-bodies, the combination of the following 130 elements, viz: a frame for supporting the operating mechanism, a rotary shaft mounted in

the said frame, a longitudinally-reciprocating and laterally-oscillating burnisher pivotally connected to the said shaft to revolve with the same, and normally and automatically maintained in a rectilinear direction with the said shaft, and projecting beyond the end of the same, and adapted to be passed through the collar to be attached and spread the tubular portion of the said collar against the inner surface of the lamp-body.

3. In a machine for attaching collars to lamp-bodies, the rotary hollow shaft A, supported in bearings, a longitudinally-reciprocating and laterally-oscillating burnisher normally and automatically maintained within the said shaft in a rectilinear direction with reference to the sides of the same, comprising a blade, C, and burnisher-tip r, and pivotally supported within the said rotary shaft by means of a pin, s³, passing through a longitudinal slot in the said shaft and through the blade C of the burnisher, the said burnisher-tip projecting beyond the end of the said shaft and adapted to pass through the collar to be attached and spread the tubular portion of the collar against the inner surface of the lamp-body, substantially as described.

4. In a machine for attaching collars to lamp-bodies, a rotary shaft, A, a laterally-oscillating and longitudinally-reciprocating burnisher upon the said shaft, and a fulcrumed arm, E, connected toward one end with the said burnisher, and adapted to control the pressure of the said burnisher upon its work independently of the will of the operator, substantially as described, and for the purpose set forth.

5. In a machine for attaching collars to lamp-bodies, the combination, with the rotary shaft A, longitudinally-reciprocating and laterally-oscillating burnisher normally and automatically maintained in a rectilinear direction with the said shaft, of a lever connected with the said burnisher, whereby the said burnisher may be advanced into a lamp-body, and a spring operating in opposition to the power exerted to advance the said burnisher into the lamp-body, to withdraw the burnisher from the same, when said lever shall be released, substantially as described.

6. In a machine for attaching metal collars to lamps, the combination, with the lever K, by means of which the burnisher is operated, through intermediate mechanism, to spread the tubular portion of the collar against the inner surface of the lamp body, of mechanism for advancing the said burnisher into and withdrawing it automatically from within the said lamp-body, said mechanism comprising, in combination, the following elements, viz: a lever, M, secured upon a loose sleeve, F', upon the shaft A, a sleeve, F, secured to the said shaft to revolve with the same, and connected with the said burnisher by means of a pin, s³, passing through a longitudinal slot in the said shaft and through the blade or exten-

sion C of the said burnisher, whereby the said burnisher may be advanced by the action of the lever K upon the lever M without moving the shaft A longitudinally, a helical spring, 70 D, encircling the shaft A, and adjusted to be contracted with the advance of the burnisher and to expand and retract automatically the said burnisher, and means for regulating the tension of the said spring, the whole being 75 constructed and arranged to operate substantially as described.

7. In a machine for attaching metal collars to lamps, the combination, with the mechanism for advancing and retracting the burnisher, of a pawl or catch, b, connected to the lever M, to move with the same, a stop, b', adjusted upon the frame of the mechanism to permit the pawl or catch b to engage with it when the moving end of the lever M shall 85 have been advanced sufficiently far against the resistance of the spring D, and a pin, b³, adjusted upon the connecting-link of the levers K and M, to disengage the pawl or catch b from the stop b' when the lever K shall have 90 been released by the operator, whereby the expansion of the spring D shall be permitted at the proper time to retract the burnisher r, and at the same time force back the lever M, substantially as described.

8. The combination, with the frame, lever M, spring D, and pawl or catch b, in a machine for attaching collars to lamp-bodies, of an air-cushion, operating to retard the reaction of the spring D upon the driving-shaft, substantially as described.

9. In a machine for attaching collars to lamp-bodies, the combination of the rotary shaft A, follower O, and a plate, L, having an opening through its center, and having the 105 material around the said opening removed, to provide a seat for an annular plate, and an annular plate, Z, the center of the opening of which shall coincide with the center of the opening in the said plate L, as and for the 110 purpose set forth.

10. The combination, with the plate L, of a machine for attaching metal collars to lamps, of the follower O, parallel to the said plate L, a lever, P, operated against the resistance of a spring to advance the said follower, whereby the lamp-body and collar shall be pressed between the said plate and follower, and operating by the recoil of the said spring to release the said lamp-body and collar, and a pawl upon the said lever engaging with a rack as soon as the desired pressure shall have been exerted against the said lamp-body to continue the pressure until released, substantially as and for the purpose set forth.

11. In a machine for attaching collars to lamp-bodies, the follower O, supported in an adjustable bearing, u', by means of a rod, f, having a longitudinal slot, f', toward one end, a link, Q, pivoted at one end to one side of 120 the said bearing, a rack, R, secured to the opposite end of the same, a lever, P, pivoted at

one end to the link Q, a lever, P', pivoted toward its center near the end of the rod f, adjustable link d, connecting corresponding ends of the levers P and P', bolt i, provided with 5 a helical spring, i', and means for regulating the same, and inserted within the lever P and through an opening in the lever P', and a dog mechanism comprising the detent i³, and means, substantially as described, for prevent-

ing and permitting engagement of the said to detent with the teeth of the said rack, the whole being constructed and arranged to operate as and for the purpose set forth.
